LOUIS HORVATH, OF NEW YORK, N. Y.

SAFETY ATTACHMENT FOR GAS STOVES.

Application filed February 17, 1926. Serial No. 88,735

This invention relates to a safety attachment for a gas stove or range, and more particularly to a gang lock for the handles of the gas valves thereof.

5 The ordinary type of gas range now commonly used has handles on the valves that control the flow of gas to the burners. With such ranges there is a danger that the valves may be accidentally opened by brushing 10 against the handles, or by children in playing or otherwise, or from other causes.

One of the objects of my invention is to provide a safety attachment having a snap catch whereby it may be readily locked in 15 place on a range to cover the valve-handles in their closed position so as to prevent them from being moved or tampered with.

Another object is to provide an attachment of this character which is simple and 20 inexpensive to manufacture, and can be readily applied to any ordinary gas range.

With these and further objects in view, the invention consists in the novel features of construction, arrangement and combination of parts, hereinafter described and claimed.

The accompanying drawings illustrate a preferred embodiment of the invention in which:—

30 Figure 1 is a front view of the attachment as applied to a gas range, the gas feed pipes being shown in section;

Fig. 2 is a vertical section on the line 2—2 of Fig. 1; and,

35 Fig. 3 is a perspective view of the attachment detached from the gas range.

Similar reference characters indicate corresponding parts throughout the several views.

40 Referring now to the drawings, 1 indicates a gas supply or feed pipe having a plurality of branches 2 leading to the burners of the range (not shown). The feed pipe is provided with the customary valves 3, one for each branch pipe, each having a handle 4 by which it may be opened or closed to control the flow of gas to the burners. These parts may all be of the usual construction.

45 50 In carrying out my invention I employ a substantially U-shaped cover 5 adapted to fit over and receive the handles when in their closed position, in which position all of the handles will be in alignment. When the

cover is placed over the handles and locked 55 in position, any further movement of the handles is prevented, and consequently the valves cannot be accidentally or unintentionally opened.

The device for locking the cover in place 60 comprises a shackle 6 pivoted or hinged at 7 to a lug 8 extending downwardly from a wall of the cover member. The free end of the shackle is provided with a spring or snap catch 9 which is preferably formed 65 with a square shoulder 10. The cover is provided with a slot or opening 11 to receive the free end of the shackle. In fastening the attachment to a gas range, the shackle is swung upon its pivot so as to 70 pass around one of the branch pipes 2 and through the slot 11. In this position the shoulder 10 of the spring 9 catches over an edge of the slot 11, thereby locking the attachment in place. It should be observed 75 that the end of the spring catch is preferably beveled to facilitate its passage through the slot. When it is desired to remove the attachment, the catch may be readily disengaged by merely pressing against the end of 80 the spring. For convenience in applying the attachment to ranges of different construction, the locking device is preferably made so as to be adjustable both longitudinally and vertically with respect of the 85 cover, and to this end the cover is preferably provided with a plurality of slots 11.

For ordinary purposes the lock afforded by the spring catch will provide sufficient security but in the case of prolonged absence, or for other reasons, it may be desired 90 to lock the cover more securely in place. This may be done conveniently by passing the shackle of an ordinary padlock through the aligned holes 12 formed in the parts 6 95 and 9.

It is to be understood that I do not limit myself to the precise construction herein shown and described as minor changes may be made therein without departing from the 100 claimed invention.

What I claim is:—

1. An attachment for locking the valve-handles of a gas range in closed position, comprising a cover adapted to fit over the 105 handles and formed with a slot, a shackle pivoted to the cover with its free end positioned to pass through the slot, and a spring

catch at the free end of the shackle for fastening it in the slot.

2. An attachment for locking the valve-handles of a gas range in closed position, comprising a cover adapted to fit over the handles and formed with a slot, a shackle pivoted to the cover with its free end posi-

tioned to pass through the slot, and a spring at the free end of the shackle formed with a shoulder adapted to engage over an edge of ¹⁰ the slot so as to fasten the shackle in the slot when inserted therein.

LOUIS HORVATH.
